ROBERT ZAHN, OF PLAUEIN, GERMANY.

JACQUARD MECHANISM FOR EMBROIDERING-MACHINES.

1,074,565.

Specification of Letters Patent. Patented Sept. 30, 1913.

Application filed July 9, 1912. Serial No. 708,495.

To all whom it may concern:

Be it known that I, ROBERT ZAHN, a subject of the German Emperor, residing at Plauen, Vogtland, in the Kingdom of Saxony, Germany, have invented certain new and useful Improvements in Jacquard Mechanism for Embroidering-Machines, of which the following is a specification.

It is well known with automatic embroidery machines to employ braking means for the needle bars in order to prevent the easily movable Jacquard needles from accidentally coming into a wrong position owing to jerks and vibrations of the machine or that the same be not hindered in the accomplishment of their object when the openings of the Jacquard card incidentally are obstructed by dust particles, paper fibers or the like.

It is thus the object of the hitherto used brake for the needle bars to secure by friction the individual needle bars in that position in which they are located at the time when the cylinder around which the Jacquard card is guided is moved toward the needles. This brake, however, is adapted to brake the needle bars not only at the aforementioned periods but constantly and there is, therefore, the drawback that the Jacquard needles, when one and the same card is repeatedly used, will mutilate the latter and in a short time render the considerably expensive cards useless.

The object of this invention is to provide a brake mechanism for the needle bars which will not constantly but only temporarily brake the needle bars, that is to say, for that short period during which it is necessary to secure the needle bars against displacement, but as soon as the needle enters the Jacquard card the respective needle bar will be released from the brake. Thereby, the Jacquard card will be spared the unnecessary strain which it suffers under the action of the hitherto used brake.

To make my invention more clear the same is more or less diagrammatically illustrated in the accompanying drawing in which—

Figures 1, 2 and 3 illustrate the operation of the brake mechanism in connection with a needle bar and the Jacquard card cylinder.

The Jacquard card *b* is led around the Jacquard cylinder *a* which is carried by members *c* slidably mounted in bearings *d*, *e* and operated through the medium of a rod *g* in well known manner. The needles *p*

are carried by needle bars *f* and project toward the perforated Jacquard card *b* so that when the Jacquard card *b* and Jacquard card cylinder *a* are moved toward the needles *p*, each needle *p* which happens to lie opposite a hole in the Jacquard card remains in its normal position, but all other needles are displaced out of their normal position into an idle position.

The brake mechanism for each needle bar *f* which I employ for the purpose of preventing the accidental displacement thereof, owing to jerking or vibration of the machine, consists of a lever arm *h* fulcrumed on a stationary part, as at *i*, and carrying at its free end a roller *k* adapted to constantly bear on the member *c* which carries the Jacquard card cylinder *a*. This member *c* is provided with a cam shaped projection *m* whereby, when the Jacquard card cylinder *a* is moved toward the needles *p*, the roller *k* will be caused to ascend the cam projection *m*, in consequence of which the lever *h* will be lifted from above the member *c*. The lever *h* carries a downwardly projecting frame *n* in which a spring actuated pin *o* is mounted that with its lower end is adapted to press on the needle bar *f* and to thereby exert a braking action thereon.

The mode of operation of the braking mechanism is as follows: Before the cylinder *a* reaches the needles *p* the braking pin *o* presses on the needle bar *f* and by friction securely holds it in position (Fig. 1). As soon, however, as the card has advanced so far that a needle *p* enters an opposite hole of the former, the cam projection *m* begins to lift the lever *h* and pin *o* through the medium of the roller *k* (Fig. 2) and gradually releases the brake pin *o* from the needle bar (Fig. 3). The pin will return into its normal position onto the bar *f*, when the member *c* moves away the Jacquard card cylinder from the needles.

What I claim and desire to secure by Letters Patent is:

1. In an embroidering machine, the combination with a Jacquard needle bar and the Jacquard card cylinder reciprocatory supporting means, of a brake mechanism for said bar controlled by said supporting means and adapted to automatically release the said bar at the moment its needle enters a hole in the Jacquard card.

2. In an embroidering machine, the combination with a Jacquard needle bar and the

- Jacquard card cylinder reciprocatory supporting means, of a brake mechanism for said bar, means on said supporting means coacting with said brake mechanism and adapted at the moment the needle of said bar enters a hole in the Jacquard card to release said bar from said brake.
3. In an embroidering machine, the combination with a Jacquard needle bar and the Jacquard card cylinder reciprocatory supporting means, of a brake mechanism for said bar, a swinging member carrying said brake mechanism and means on said supporting means coacting with said swinging member and adapted to automatically release the said bar from said brake at the moment its needle enters a hole in the Jacquard card.
4. In an embroidering machine, the combination with a Jacquard needle bar and the Jacquard card cylinder reciprocatory supporting means, of a movable member, a brake for said needle bar carried by said member and a cam on said supporting means coacting with the said movable member and adapted at the moment the needle of said bar enters a hole in the Jacquard card to release said bar from said brake.
5. In an embroidering machine, the combination with a Jacquard needle bar, the Jacquard card cylinder and the reciprocating means supporting the latter, of a spring actuated brake for the said needle bar and means on said supporting means whereby the said bar will be automatically released at the moment its needle enters a hole in the Jacquard card.
6. In an embroidering machine, the com-

bination with a Jacquard needle bar, the Jacquard card cylinder and the reciprocating means supporting the latter, of a movable member, a spring actuated brake for the needle bar carried by said member and means on the supporting means whereby the said bar will be automatically released at the moment its needle enters a hole in the Jacquard card.

7. In an embroidering machine, the combination with a Jacquard needle bar, the Jacquard card cylinder and the reciprocating means supporting the latter, of a swinging member, a spring actuated brake for said bar carried by said member and a cam on said supporting means coacting with said swinging member and adapted at the moment the needle of said needle bar enters a hole in the card to lift the said brake from the needle bar.

8. In an embroidering machine, the combination with a Jacquard needle bar, the Jacquard card cylinder and the reciprocating means supporting the latter, of a swinging arm, a spring actuated braking pin adapted to normally brake the said needle bar and a cam on the supporting means adapted to coact with said arm and to lift the latter and the said braking pin from the needle bar at the moment the needle of the latter enters a hole in the Jacquard card.

In testimony whereof I affix my signature in presence of two witnesses.

ROBERT ZAHN.
